United States Patent Office

Des. 234,239
Patented Feb. 4, 1975

234,239

SOFA

Stapleton Long, 1629 Christmas Drive,
Morristown, Tenn. 37814

Filed Nov. 28, 1972, Ser. No. 310,017

Term of patent 14 years

Int. Cl. D6—01

U.S. Cl. D6—63

FIG. 1.

FIG. 2.

FIG. 1 is a view, in front elevation, of a sofa showing my design; and

FIG. 2 is a view, in side perspective, of the sofa of FIG. 1.

The sofa back is plain and conventional throughout and the side not shown is identical to that shown.

I claim:

The ornamental design for a sofa, as shown and described.
